UNITED STATES PATENT OFFICE.

GEORGE L. DIXON, OF ALHAMBRA, CALIFORNIA.

AIR-HEATER.

1,359,234.

Specification of Letters Patent. Patented Nov. 16, 1920.

Application filed January 8, 1918. Serial No. 210,819.

To all whom it may concern:

Be it known that I, GEORGE L. DIXON, a citizen of the United States, residing at Alhambra, in the county of Los Angeles and 5 State of California, have invented a new and useful Air-Heater, of which the following is a specification.

This invention relates to stoves or heaters designed to supply heated air and an object 10 of the invention is to provide a simply constructed heater which will have a relatively small consumption of fuel for the amount of air which it heats.

Another object is to make provision for 15 heating the space around the lower portion of the heater so as to heat the floor and the space immediately above the floor.

Another object is to so construct the 20 heater that it may be readily cleaned inside.

Other objects and advantages will appear in the subjoined detail description.

The accompanying drawings illustrate invention:

25 Figure 1 is a side elevation of the heater.

Fig. 2 is a vertical mid section of the heater.

Fig. 3 is a plan section on line indicated by x^3-x^3 , Fig. 2.

30 Fig. 4 is a plan section on line indicated by x^4-x^4 , Fig. 2.

There is provided a jacket comprising a cylindrical casing 1 and a top 2, there being a flue opening 4 near the upper end of the 35 casing 1 and communicating with a flue 5, and there being an annular opening 6 between the lower edge of the casing 1 and a deflector plate 3.

40 Mounted in the lower portion of the casing 1 is an air chamber 7 having ports 8 in its side communicating with radially extending tubes 9 which project through openings 10 in the casing 1. The lower portion 11 of the air chamber 7 is substantially in the form of an inverted truncated cone so as to spread the flame from a burner 12 and reflect the heat downward and outward through the opening 6. The burner 12 is supplied with fuel through a pipe 13 which 45 may be provided with a valve 14. The burner may be formed in sections, as shown, interfitting one another, the lower section 15 having a web 16 into which is threaded a bolt 17. The upper end of the bolt 17 50 passes through a hollow boss or stud 18 projecting upward from the top of the up-

per burner section 19 and is provided on its projecting end with a nut 20 which engages the boss to hold the sections together. The boss 18 projects through a hole 21 in the lower end of the air chamber 7 and a nut 22 is screw-threaded onto the boss 18 against said lower end so as to securely fasten the burner and air chamber to one another. The burner jets 23 are positioned around the margin of the upper burner section 19 and said jets preferably extend at an angle upward and outward so as to direct the flame along the under surface of the air chamber 7. This construction provides for economical heating of the air in the air chamber and also for reflecting heat downward and outward through the opening 6.

70 The cone-shaped portion of the air chamber 7 is provided with ports 24 communicating with the upper ends of hollow legs 25 in the form of tubes which extend aslant downward and outward through the openings 6, there being notches 26 in the bottom 3 to partly accommodate the legs. The deflector plate 3 connects the legs to one another and forms a brace for the legs. The legs 25 are provided near their lower ends with ports 27 and these ports are preferably 75 on the inner sides of the legs so that they cannot be readily seen when the heater is in use. The casing 1 rests on the legs 25 and the legs thus support said casing and said legs also support the air chamber.

75 The chamber 7 is of somewhat smaller 80 diameter than the casing 1 so as to form segmental passages 28 between adjacent tubes 9. The top of the air chamber 7 may be flat and supported by the flat top is a series of baffle plates 29. The lowermost 85 baffle plate is provided with a central opening 30 and with feet 31 loosely resting on the top of the air chamber. The next to the lowermost baffle plate is also provided with feet 31 which loosely rest on the lowermost 100 baffle plate. All but the lowermost baffle plate are provided at their marginal portions with ports 32, alternate plates having these ports arranged at opposite sides of the heater. All but the two lower baffle 105 plates are provided with feet 33 of tubular form and the lower end of each foot rests on the next lower baffle plate. Thus the baffle plates support one another and the products of combustion pass upward 110 through the ports 32 and to and fro from side to side of the casing. Owing to the

provision of the tubular feet 33 the products of combustion do not pass directly across from the port 32 in one baffle plate to the port in the next higher baffle plate but circulate around the feet 33 in the space between adjacent baffle plates, thus maximizing the heating effect. The top 2 is removable and by removing the top the baffle plates 29 may be removed one at a time for cleaning or any other purpose.

In practice, the valve 14 will be opened and the fuel will be lighted at the burner and the products of combustion will pass upward between adjacent baffle plates, thus parting with heat and said products of combustion will then pass through the flue 5 to the chimney, not shown, to which the flue is connected. The air in the chamber 7 will be heated and will pass outward through the tubes 9, being replaced by cooler air flowing into the legs 25 through the ports 27 and from said legs through the ports 24 into the air chamber. Thus cooler air is being constantly removed from the space immediately above the floor and this cooler air is replaced by the warm air passing from the lower portion of the jacket outward and downward through the opening 6 between the legs 25. A central opening 34 in the deflector plate 3 accommodates the burner 12 and is preferably slightly larger than the burner so as to admit air between the plate and burner and this air when heated in the lower portion of the casing may pass outward through the opening 6.

From the foregoing it is clear that the greater portion of the heated air from the heater in fact practically all of it, will discharge from the lower part of the heater so that the space just above the floor of the room in which the heater is placed will be well heated.

I claim:

1. A heater having outwardly and downwardly inclined supporting hollow legs provided with an opening at their lower end forming an air intake, a cylindrical casing having its lower end open and mounted upon said legs, the legs extending upwardly

within said casing and communicating with an air chamber mounted in said casing, air vents extending outwardly from said air chamber to discharge heated air, a deflector plate mounted between said legs and spaced to provide an annular opening between the lower edge of said casing and said plate, a burner mounted below said air chamber and extending through an aperture formed in said deflector plate, said aperture being slightly larger than the burner to provide an air intake.

2. A heater comprising a casing having its lower end open and mounted on legs, an air heating chamber mounted in said casing and provided with vents, a deflector plate for said heater mounted between said legs and spaced to provide an annular opening between said plate and said casing, an aperture formed in said deflector plate, a burner mounted below said chamber and extending through said aperture, said aperture being larger than said burner to form an air intake port.

3. In a heater, a casing having its lower end open and mounted upon legs, a main air heating chamber having an intake and an outlet, a burner, an auxiliary air heating chamber formed below said main air heating chamber and a deflector plate secured between said legs and spaced from the lower edge of said casing whereby there is provided an outlet for said auxiliary chamber.

4. In a heater, a casing having its lower end open, legs supporting the casing, a main air heating chamber having an intake and an outlet, a burner, an auxiliary air heating chamber formed below the main air heating chamber, and a deflector plate beneath the casing spaced from the lower edge thereof, whereby there is provided an outlet for the auxiliary chamber.

Signed at Los Angeles, California, this 31st day of December, 1917.

GEORGE L. DIXON.
